US00D959336S

(12) **United States Design Patent** (10) **Patent No.:** **US D959,336 S**
(45) **Date of Patent:** **** Aug. 2, 2022**

(54) **PEDAL BRACKET**

(71) Applicant: **Foshan Yupinxi Trading Co., Ltd.,**
Guangdong (CN)

(72) Inventor: **Jianzhao Liang**, Guangdong (CN)

(**) Term: **15 Years**

(21) Appl. No.: **29/827,784**

(22) Filed: **Feb. 22, 2022**

(51) LOC (13) Cl. **12-11**

(52) U.S. Cl.

USPC **D12/114**

(58) **Field of Classification Search**

(57) **CLAIM**

The ornamental design for a pedal bracket, as shown and described.

DESCRIPTION

FIG. 1 is a perspective view of the pedal bracket showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the pedal bracket where the pedal bracket is in use.

The broken lines shown in the drawings are included for the purpose of illustrating portions of the pedal bracket that form no part of the claimed design.

1 Claim, 9 Drawing Sheets
